UNITED STATES PATENT OFFICE

95,407

DESIGN FOR A BUILDING

Howard W. Godwin, St. Louis, Mo.

Application February 4, 1935, Serial No. 55,245

Term of patent 14 years

To all whom it may concern:

Be it known that I, Howard W. Godwin, a citizen of the United States, residing at St. Louis, in the State of Missouri, have invented a new, original, and ornamental Design for a Building, of which the following is a specification, reference being had to the accompanying drawings, forming part thereof.

Figure 1 is a top plan view of a building, showing my new design.

Figure 2 is a view in front elevation thereof.

Figure 3 is an elevational view, looking at one side of the building.

Figure 4 is a rear elevational view.

Figure 5 is an elevational view, looking at the remaining side of the building.

Figure 6 is a horizontal sectional view taken through Figure 1 approximately on the line 6—6.

I claim:—

The ornamental design for a building, as shown and described.

HOWARD W. GODWIN.
